G. FRIEL.
STREET CENTER CROSSING INDICATOR.
APPLICATION FILED JULY 30, 1917.

1,295,021.

Patented Feb. 18, 1919.

UNITED STATES PATENT OFFICE.

GRANT FRIEL, OF LOS ANGELES, CALIFORNIA.

STREET-CENTER-CROSSING INDICATOR.

1,295,021.

Specification of Letters Patent.

Patented Feb. 18, 1919.

Application filed July 30, 1917. Serial No. 183,412.

To all whom it may concern:

Be it known that I, GRANT FRIEL, a citizen of the United States, residing at the city of Los Angeles, county of Los Angeles, State 5 of California, have invented new and useful Improvements in Street-Center-Crossing Indicators, of which the following is a specification.

In communities where there are many 10 automobiles in use, it has been found necessary to require the drivers thereof to pass to the right of the intersection of the center line of crossing streets when turning from one street into the cross street and various 15 devices have been used to indicate where such center point is located. Many of these devices have been found dangerous at night and useless.

It is the object of my invention to provide 20 a street center crossing indicator that can be seen both by day and at night and which will not be dangerous at any time and will not only indicate the point of the crossing of the center lines of the streets but which 25 will also give the names of such crossing streets.

In the drawings forming a part of this application;

Figure 1 is a top plan of a street crossing 30 with my center indicator in place.

Fig. 2 is a section on the line 2—2 of Fig. 1.

Referring to the drawings, Fig. 1 shows my street center line crossing indicator installed at the intersection of the center lines of First and Main streets where a pit 5 is first dug. An electrical conduit 6 with electric wires not shown is then put in the street and terminates in a lamp a little above the 40 street surface. A reflector 8 is mounted on conduit 6. These parts would be properly positioned in the pit as shown in Fig. 2. The pit is then nearly filled with plastic concrete 9, after which the cover and other 45 parts are put in place. The cover consists of a raised central portion of any suitable shape. In the drawings this central portion consists of a hollow dome 10 which is the segment of a hollow sphere. Projecting outward from the bottom of the dome 10 is an annular flange 11 with holes therein for the reception of bolts 12 which have secured thereon nuts 13. The dome and flange are preferably integral and of heavy cast iron 55 and after the bolts are positioned in the flange, the cover and bolts are forced down upon and into the plastic cement which when it hardens holds the nuts firmly positioned therein, thereby permitting the removal of the bolts when it is desired to take 60 off the cover to replace the lamp or to effect other repairs or to cleanse the interior of the dome. Dome 10 has four apertures 14 which are crossed by the center lines of the streets and lamp 7 is visible through 65 these apertures by a person approaching the dome on these lines. These apertures for distinction may be termed name apertures as the names of the streets are cut or stenciled in the body portion 15 of sheet metal plates 70 whose base portions 16 are removably secured to the dome by screws 17. The top of the body portion is turned over to receive and hold a pane of glass or other transparent material 18 to keep dirt or other matter from passing through the sign portion 75 15. The interiors of apertures 14 are closed preferably by sheets of red glass or other transparent colored material which are held secured to the dome by screws 20 and 80 washers 21. Instead of stenciled name plates, the names of the streets could be painted on transparent material. In the top of the dome is a central light aperture whose outer surface is closed by a plain or magnifying glass disk 22 and whose inner surface is closed by a red glass disk 23 or other colored transparent material or semitransparent material. Disk 23 is held positioned by screws 24 and washer 25. It will be understood that while it is not intended that vehicles shall pass over the dome it is made strong enough to support such vehicles should they pass over the same. I have shown the dome in the shape of the segment 95 of a hollow sphere as I prefer that shape but it may be of any suitable shape. I may also use my indicator on the center lines of streets crossing railways and instead of the street name being shown in the apertures 100 there would be shown the letters R R X or other suitable term to show the traveling public that it was coming to a rail-road crossing. By the use of a lighted lamp in the dome at night, the turning point would 105 be shown and the name of the street at which the driver wished to turn would also be shown before the turning point was reached. A light other than an electric light could be used in the dome if desired. 110 The reflector could be omitted but the indicator would not be as good as with it.

Where cheapness is desired the metal plates showing the names of the streets may be omitted.

Having described my invention what I claim is;

1. A crossing indicator comprising a light at surface of the street; a protective covering for said light having apertures through which said light can be seen, said covering being of opaque material strong enough to protect the light from the street traffic; transparent closures for said apertures; and opaque indicia on said closure, said indicia being visible through said apertures.
- 18 2. A crossing indicator comprising a light at the surface of the street; a protective covering for the said light having apertures through which said light can be seen, said covering being of opaque material strong
- 20 enough to protect the light from the street

traffic; and transparent closures of colored material for said apertures, said closures having opaque indicating characters thereon, said indicia being visible through said apertures.

3. A crossing indicator comprising a pit excavated at the crossing of the center lines of two streets; an electric lamp mounted in said pit; concrete in said pit; a dome having an annular flange detachably secured to said concrete, said dome having apertures through which said lamp may be seen; colored transparent closures for said apertures secured to said dome; and opaque indicating characters on said closures, said characters being visible through said apertures.

In witness that I claim the foregoing I have hereunto subscribed my name this 19th day of July, 1917.

GRANT FRIEL.
